PULP MOLDING

George W. Swift, Jr., Bordentown, N. J., assignor
to George W. Swift, Jr., Inc., Bordentown,
N. J., a corporation of New Jersey

Application March 13, 1935, Serial No. 10,789

7 Claims. (Cl. 92—54)

The invention relates to the molding of products from wet pulp or similar fibrous material adapted to be carried in a water suspension, and aims primarily to provide a molding apparatus and process involving the use of but a single mold of a special character, through which water from the suspension is drawn or sucked by difference in fluid pressure on the opposite faces of the mold in such manner that a sheet of the pulp fibres is progressively built up and compacted by liquid pressure, on one face of the mold, without requiring any mating mold or mechanical pressure in the main product forming operation. The invention is particularly useful in connection with the molding of products such as cups or other deep receptacles involving the use of a mold which presents a highly irregular surface to the pulp suspension. Prior efforts to mold pulp articles of the above character have involved the use of molds which are expensive to construct, and in operation it has been difficult to form the product sufficiently uniformly on different parts of the mold. Molds constructed of perforated metal sheets or metal screening for example are exceedingly expensive, and are not adapted to be formed into markedly irregular shapes, since marked distortion of the sheets distorts the openings to varying degrees, and involves patchwork on the surface of the mold which renders it irregular and variable in its water receiving qualities. Molds of spaced metal laminations likewise are costly, and involve expensive machining operations particularly if markedly irregular shapes of product are desired, and it is difficult to build up the product regularly since the water passages of the mold are aligned in direction and therefore afford variable facility of flow of the water when the surface of the mold is irregular. These metal molds furthermore necessitate the use of relatively large water passages which produce a rough surface on the product.

The invention aims to obviate the above difficulties, especially in respect to the molding of deep or otherwise highly irregular products.

Further objects and advantages of the invention will be in part obvious and in part specifically referred to in the description hereinafter contained which, taken in conjunction with the accompanying drawing, discloses one form of apparatus suitable for use in carrying out the invention; such disclosure however is to be regarded as merely illustrative of its principles. In the drawing—

Fig. 1 is a vertical sectional view showing a

molding apparatus constructed in accordance with the invention, in operative position in a receptacle containing pulp suspended in water.

Fig. 2 is a vertical section of a mold of the type used in practicing the invention and showing a 5 molded product in its formed position.

Fig. 3 is a bottom plan view of the mold shown in Fig. 2.

In carrying out the present invention, one face 1 of a mold of porous, stone-like material is exposed to a liquid suspension of the pulp which is under atmospheric pressure, while the opposite face 2 of the mold is subjected uniformly over its active area to the action of a vacuum, whereby the water of the suspension is gradually drawn or sucked through the innumerable pores of the mold, by the difference in fluid pressures existing on opposite sides of the mold. Reference herein to the employment of a vacuum is to be understood as using the word in a relative sense to include fluid pressure differentials between the opposite faces of the mold, of a like order to the above described mode of operation. As shown in Fig. 1 for example, the mold may form one wall of a hollow box-like housing 3, having a vacuum chamber 4 therein which is exhausted through pipe 5, and the molding apparatus thus constituted may be immersed in a suitable receptacle 6 containing the pulp suspension 7. The latter will be quite dilute, containing for example, about 98% water and 2% pulp by weight.

The face 1 of the mold is shaped to conform to the shape of product desired to be made, the illustrated mold being designed for the formation of egg containing trays, and having a flange 8 extending outwardly around it, and held against a ledge 9 extending around the interior of housing 3, by a clamping plate 10 and bolts 11. The face 1 of the mold is also provided with a series of individual receptacle forming portions 12 which project relatively deeply into the pulp suspension, and between these portions 12 are interposed a series of relatively narrow and deep conical recesses 13, which form in the molded product a series of supporting posts interposed between the egg containing receptacles. As the mold is viewed in Fig. 3, the receptacle forming portions 12 thereof are in what may be termed the foreground, while the recesses 13 project deeply into the face 1 of the mold, and there are also a series of grooves or valleys 14 which extend less deeply into the face of the mold between the receptacle-defining portions 12 thereof, and define the walls 55

of the product which are between adjacent receptacles.

I have found that by subjecting a mold of the above character to a moderate fluid pressure differential on its opposite faces as above described, water from a pulp suspension will be drawn quite uniformly through the body of the mold even though the latter be highly irregular in shape, and that the pulp will build up on the surface of the mold in the form of a layer or sheet which is substantially uniform throughout the various parts of the mold as to physical characteristics and strength, the relative liquid pressure against the outer surface of the pulp sheet, making it relatively strong and tough, without unduly clogging the pores of the mold or blocking or concentrating the building up of the pulp layer in different local areas of the mold so as to form an objectionably irregular product. The rate at which the layer or sheet is built up will depend upon the fluid pressure differential used, and the thickness of the sheet will be in proportion to the amount of water passed through the mold.

A mold of the above character is not directional to any substantial extent, in respect to its qualities of affording passage for the water through its pores, and thus the fibrous sheet may be built up quite uniformly even though the mold is highly irregular in shape, since the suspension always flows in a direction substantially perpendicular to the various individual surface areas on the mold upon which the pulp particles are built up. The pores furthermore are so fine that a comparatively smooth surfaced product may be obtained, and if desired the surface of the molded product which is exposed to the pulp suspension, may be further finished off by the application of a couch thereto as described in my prior Patent No. 1,983,324, dated December 4, 1934, the product being finally separated from the mold by a pressure pulsation in the chamber 4, as also described in said prior patent. The product usually will next be subjected to a drying operation, to remove excess moisture therefrom.

The face 2 of the mold as well as its face 1 may be conformed substantially to the shape of the product to be molded, thereby producing a mold which is substantially uniform in thickness in the directions of travel of the water through its pores, and promoting the uniformity of the product. The rate of deposit of the fibres on local areas of the mold moreover may be controlled by altering the resistance of the pores to the passage of the water, at the desired points. Pores of larger or finer size may be employed at such points, or if the thickness of the mold be materially increased or decreased at such points, the rate of deposit of the fibres will be relatively greater or less. For example in the use of a mold of the construction previously described, the pulp layer may tend to build up somewhat more rapidly towards the bottoms of the relatively deep and narrow valleys 14 or towards the bottoms of the deep recesses 13 and this tendency may be counteracted by providing pores of finer porosity at such points, or thickening up the mold at such points.

A mold of the above character may be produced by simple and inexpensive molding operations, using as a base silica or similar granular material such as is employed in the manufacture of abrasives, mixed with a suitable binder such

as feldspar and clay to form a plastic mass which can be readily molded into the desired shape. The mold may then be heated to a high temperature sufficient to fuse the clay and thus produce an open, porous structure of a refractory stone-like nature, which will be strong and durable. At points where it is desired to reduce the rate of deposit of the fibres as above described, finer grains of the base material may be employed, as indicated at 15 in the drawing.

A heat resistant mold as above described has the advantage that if its pores through long continued use become clogged with fibres or other deposits, they may be eliminated without injury to the mold by heating it to a temperature high enough to reduce the clogging matter to a form in which it may be blown out by air pressure.

The present specification contains certain subject matter which is also disclosed in my prior copending application Serial Number 701,967, filed December 12, 1933, and entitled "Pulp molds and process of making same".

This invention has more particularly to do with the molding of articles of irregular shape, i. e., having raised portions and/or depressions, as contrasted to flat sheets which may be easily formed by well-known processes.

While the invention has been described as its steps are carried out by the aid of the specific apparatus above described, it should be understood that changes may be made therein without departing from the invention in its broader aspects, within the scope of the appended claims.

I claim:

1. An apparatus for forming wet pulp articles of irregular contour, having a receptacle containing a thin pulp suspension in water of the character described, a housing having a vacuum chamber, a mold of porous stone-like material forming part of the walls defining said chamber and having one of its faces exposed to said chamber, and its other face recessed to conform to the shape of the article to be formed, said mold having pores of finer size adjacent certain recessed portions thereof, the last mentioned face of the mold being immersed in said liquid suspension of the pulp, whereby pulp will be progressively drawn from the suspension and deposited in sheet form on the last mentioned face of the mold, by the vacuum action of the chamber, with relatively reduced deposit of pulp on said last above mentioned portions of the mold.

2. An apparatus for forming wet pulp articles of irregular contour, having a receptacle containing a thin pulp suspension in water of the order of 98% water and 2% pulp, a housing having a vacuum chamber, a mold of porous stone-like material forming part of the walls defining said chamber and having one of its faces exposed to said chamber and its other face of irregular contour and conforming to the shape of the article to be formed, the last mentioned face of the mold being immersed in said liquid suspension of the pulp, whereby pulp will be progressively drawn from the suspension and progressively built up in a sheet of substantially uniform thickness on the last mentioned face of the mold with the outer surface of the sheet in contact with the supply of pulp-in-water suspension contained in said receptacle, in accordance with the amount of water drawn through the mold by the vacuum action of the chamber.

3. The method of forming wet pulp articles of irregular contour from a thin liquid suspension

of the pulp of the order of 98% water and 2% pulp, which comprises immersing an irregular face of a porous body of stone-like material in a supply of said suspension, and simultaneously exposing another face of such body to the action of a vacuum whereby pulp will be progressively drawn from the suspension and progressively built up in a sheet of substantially uniform thickness on the first mentioned face 5 of the mold, with the outer face of the sheet in contact with the supply of pulp-in-water suspension, in accordance with the amount of water drawn through the mold by the aforesaid vacuum action.

10 4. An apparatus for forming wet pulp articles of irregular contour, having a receptacle containing a thin pulp suspension in water of the order of 98% water and 2% pulp, a housing having a vacuum chamber, a mold of porous stone-like material forming part of the walls 15 defining said chamber and having one of its faces exposed to said chamber and its other face of irregular contour and conforming to the shape of the article to be formed, the last mentioned face of the mold being immersed in said liquid suspension of the pulp, whereby pulp will be progressively drawn from the suspension and progressively built up in a sheet of substantially uniform thickness on the last mentioned face 20 of the mold with the outer surface of the sheet in contact with the supply of pulp-in-water suspension contained in said receptacle, in accordance with the amount of water drawn through the mold by the vacuum action of the chamber, the first mentioned face of said mold 25 also conforming substantially to the shape of the article to be formed.

5. An apparatus for forming wet pulp articles of irregular contour, having a receptacle containing a thin pulp suspension in water of the order of 98% water and 2% pulp, a housing having a vacuum chamber, a mold of porous stone-like material forming part of the walls 30 defining said chamber and having one of its faces exposed to said chamber and its other face of irregular contour and conforming to the shape of the article to be formed, the last mentioned face of the mold being immersed in said liquid suspension of the pulp, whereby pulp will be progressively drawn from the suspension and progressively built up in a sheet of substantially uniform thickness on the last mentioned face of the mold with the outer surface of the sheet 35 in contact with the supply of pulp-in-water sus-

pension contained in said receptacle, in accordance with the amount of water drawn through the mold by the vacuum action of the chamber, certain portions of the mold being so constructed and arranged as to increase the resistance to the passage of water therethrough, thereby to adjust the rate of deposit of pulp on said last above mentioned portions as compared to the remaining active area of the mold. 5

6. An apparatus for forming wet pulp articles 10 of irregular contour, having a receptacle containing a thin pulp suspension in water of the order of 98% water and 2% pulp, a housing having a vacuum chamber, a mold of porous stone-like material forming part of the walls 15 defining said chamber and having one of its faces exposed to said chamber and its other face of irregular contour and conforming to the shape of the article to be formed, the last mentioned face of the mold being immersed in said liquid suspension of the pulp, whereby pulp will be progressively drawn from the suspension and progressively built up in a sheet of substantially uniform thickness on the last mentioned face 20 of the mold with the outer surface of the sheet in contact with the supply of pulp-in-water suspension contained in said receptacle, in accordance with the amount of water drawn through the mold by the vacuum action of the chamber, certain portions of the mold being relatively 25 thick in the direction of travel of water therethrough, thereby to adjust the rate of deposit of pulp on said last above mentioned portions as compared to the remaining active area of the 30 mold. 35

7. A suction box for pulp molding machines of the immersion type, comprising a housing having a vacuum chamber, a mold composed of a unitary mass of material having a porous structure, said mold being detachably secured to said housing and being of substantial thickness and rigidity, said mold also forming part of the walls defining said chamber and having its inner face exposed to said chamber and its outer face of irregular contour and conforming to the shape of the article to be formed thereon, whereby the vacuum action of said chamber operating through said mold progressively builds up pulp in a sheet of substantially uniform thickness on 45 the last mentioned face of the mold, during immersion of said mold in a pulp in water suspension. 50
